UNITED STATES PATENT OFFICE.

MELVILLE E. PETERS, GEORGE H. FATH, AND ALBERT F. MILLER, OF DENVER, COLORADO, ASSIGNEES TO THE PETERS PATENT RIGHTS COMPANY, OF DENVER, COLORADO, A CORPORATION OF COLORADO.

END-TURN-IN WIPER FOR WRAPPING THE END EDGES OF BOXES WITH GUMMED BLANKS.

1,251,818.

Specification of Letters Patent.

Patented Jan. 1, 1918.

Original application filed November 5, 1915, Serial No. 59,860. Divided and this application filed September 25, 1916. Serial No. 122,064.

To all whom it may concern:

Be it known that we, MELVILLE E. PETERS, GEORGE H. FATH, and ALBERT F. MILLER, citizens of the United States of America, residing at the city and county of Denver and State of Colorado, have invented a new and useful End-Turn-In Wiper for Wrapping the End Edges of Boxes With Gummed Blanks, of which the following is a specification.

Our invention relates to a new and improved type of end turn-in wipers for turning in the exposed edges of blanks that project above the top edges of boxes that have had their sides and ends wrapped with a gummed blank, the edges of which are left projecting above the top edges of the box, and the objects of our invention are:

First. To provide an automatically operating, engaging, centering, seating and folding in and wrapping mechanism for wrapping the ends of blanks over, into and against the interior surfaces of the opposite ends of partially wrapped boxes.

Second. To provide means by which the folding in and wrapping of the opposite ends of boxes is done in intermittently acting movements that enable the boxes to be received, wrapped and discharged with great rapidity and with a smooth, tightly wrapped finish.

We attain these objects by the mechanism illustrated in the accompanying drawings, in which:

Figure 1 is a vertical, longitudinal, sectional view through a portion of a box wrapping machine, showing the improved end turn-in mechanism and the operating mechanism therefor.

Fig. 2 is a transverse, vertical, sectional view through the frame shown in Fig. 1 and showing the mechanism therein in end elevation.

Fig. 3 is a view of a coöperating pair of head blocks which carry the end turn-in mechanism, one of said head blocks and its mechanism being shown in section, while the other is shown in side elevation.

Fig. 4 is a front view of one of the head blocks.

Fig. 5 is a vertical, sectional view through a portion of the arm which supports the end

turn-in mechanisms, together with a portion of one of the hollow standards for said arm and shafts, which pass through the said standard.

Fig. 6 is a top view of a member of one of the end turn-in mechanisms.

Figs. 7 and 8 are perspective views respectively of a stayed corner box and unstayed corner box. And

Fig. 9 is a plan view of one of the blank wrappers.

Similar letters of reference refer to similar parts throughout the several views.

Referring to the drawings:

The mechanism illustrated in Fig. 1 embodies our invention, and in this figure, as well as in all of the other figures of the drawings, the letters B and C designate the end turn-in mechanisms in general. These end turn-in mechanisms are similar to those illustrated and described in our pending application, Serial Number 59,860, filed November 5, 1915, for an automatically operating multiple stage treatment box wrapping machine, and this application is a divisional part of that application and has been confined strictly to the end turn-in mechanism of that application. Attention is also called to applicants' application Serial No. 122,059, filed Sept. 25, 1916.

We have found it necessary, however, to illustrate certain features of that application which are so coöperatively connected with the end turn-in mechanism as to make their operative functions unintelligible except they be coöperatively illustrated with them. To this end our end turn-in wiper mechanism is arranged to receive boxes between them that vary in size from about $1\frac{1}{2}$ inches wide to three inches long to about 12 inches wide by about 20 inches long. The boxes adapted to be wrapped are pasteboard boxes either with stayed or unstayed corners, as shown in Figs. 7 and 8, and the blanks or labels are preferably made of thin, smoothly calendered, white plain paper cut out into a form as shown in Fig. 9, and they are coated with gum, either wholly or partially on one side.

The blanks or labels are gluingly wrapped or covered around and against the outside surfaces of the boxes before they are sub-

mitted to our present end turn-in mechanism, and they are fed either by hand or by any suitable automatically operating mechanism between our end turn-in mechanisms, 5 each box having the edges of the blank projecting above the edges of the box far enough to be folded over, into and wrappingly glued against and to the interior surfaces of the opposite ends of the box.

10 After each box has had its open end edges wrapped, it is discharged from our present end wrapping mechanism.

Our end turn wrapping mechanism operates in two intermittent wrapping movements that are spaced to act at a few seconds apart, between which acts side turn-in mechanism moves against and acts co-operatingly with our herein described end turn-in mechanism to properly wrap the open edges of 15 each box. The side turn-in mechanism does not, however, form a part of our present invention and it is not either illustrated or described herein; and we have not described the means for feeding the partially wrapped 20 boxes to and for discharging the completely wrapped boxes from our present end turn-in wrapping mechanism, as they do not form a part of it. This particular mechanism, however, is illustrated in our pending application, 25 Serial No. 30,471, filed May 25, 1915.

The object of our present invention is the mechanism that wraps the projecting ends of the blanks into and against the interior surface of the open edges of the partially wrapped boxes, and it does not appertain to the means by which the partially wrapped 30 boxes are fed to the end wiper mechanism or to the means by which they are fed away from it after they have been wrapped. Consequently the boxes are fed by any suitable 35 means against a stop A, which is positioned to receive them, from which point the box is then moved forward one inch into position to have its upper ends turned in and 40 wrapped against the inside of the box. At the time the box is engaged by the front end turn-in mechanism and its forward movement of about an inch against the rear head block C has commenced, the stop arm A is 45 swung down away from the box by its operating mechanism, which does not form a 50 part of our present invention.

The first step treatment of turning in the 55 ends of the blanks is performed automatically as follows:

The blank edge turning mechanism under which the box has to pass has a horizontal reciprocal movement that enables it to occupy a position at a short distance from the 60 position the box stops at when it strikes the stop arm and the instant the box is stopped by the arm A, the head block supporting arm D drops and a block 1 on the end turn-in mechanism B is moved up against the box 65 and pushes it against a similar block 2 car-

ried by the opposite end turn-in mechanism. When this reciprocating end turn-in mechanism moves forward, the taper sole portion of its shoe engages the vertical edge of the blank that projects vertically above the box, 70 as shown in Fig. 1, and pushes it over into the box into a position substantially horizontal and at right angles to the sides of the box, and as the box is moved into operative relation to the opposite blank turn-in end 75 mechanism, which is fixed against longitudinal movement relative to the position of the box to receive it, the adjacent vertically projecting end of the blank strikes against the taper sole of the shoe, as the box is 80 pushed by the opposite block 1 against the block 2, and this edge of the blank folded over the edge of the box as the box moves under it into a substantially horizontal position. The two opposite blank end turn-in 85 mechanisms both move vertically upward above and away from the end edges of the box and leave these free ends of the blank standing folded over into the box in horizontal planes at substantially right angles to 90 the ends of the box.

The box and blank turning-in mechanism comprises two vertically positioned head blocks B and C, which are arranged to face each other.

The end turn-in mechanism C is fixed relative to the frame of the machine, while the end turn-in mechanism B has a short reciprocal horizontal movement by which it engages and moves the box against the abutment block of the turn-in mechanism C. After the box has been moved by the movable head block against the fixed head block, it is gripped and held rigidly until the edges of the projecting vertical edges of the blank are completely wrapped in the box. The two head blocks B and C are supported by and depend from an overhead arm D, which is positioned above the table over its center and extends longitudinally along its 105 entire length from adjacent to its first stage mechanism. This arm has a short, vertical reciprocal movement that is imparted to it by a cross head 3, that is raised and lowered by a cam 4. This cross head comprises two 110 cylindrical hub members 5, which are connected by a bar 6, having a central opening 7. Within the hubs are secured the lower ends of two tubular vertical hollow standards 8, the upper ends of which are secured 115 in hub portions 9 of the overhead arm D by pins 10, which pass through the said hubs and through the standards. The opening in the bar of the cross head receives a worm gear 11, through which the threaded upper 120 end of a circular bar 12 passes, the lower end of which is secured to a cam fork 13 having a roller which enters a groove in the cam disk 4, and in this manner the cross head and the overhead arm are raised and 125 130

lowered for a purpose to be hereinafter explained. Upon the hub portions of the cross head are bearings 14, in which is mounted a horizontal shaft 15, having a worm pinion 16, which meshes with the worm gear 11, carried by the cross head. The outer end of this shaft 15 carries a hand wheel 17, by turning which the worm pinion 16 is caused to turn the worm gear 11 in the cross head 3, whereby the threaded rod 12 may be lengthened or shortened to suit the depth of various sized boxes.

The overhead arm is provided with a fixed slideway bar 18, that is secured to its bottom 15 in position to receive the head block C, and with a slideway bar 19 that has a short reciprocal movement, it being slidably mounted on bolts 20, which extend through the arm. The head block C is adjustably mounted on the slide bar 18 and it is secured thereon by a set screw 21 in a position to receive each different size box that the machine will wrap.

The head block B is also adjustably mounted on the movable slideway 19 and is secured thereon in adjusted positions by a set screw 22. Both head blocks are provided with guideways 23 that straddle their slideway bars, and are secured over the side edges 30 of the slideways by cap strips 24 that are secured to their opposite sides. As illustrated, these head blocks are positioned on their respective slideways in positions to receive between them the largest box the machine will wrap. The reciprocating slideway bar 19 is provided with a number of gear teeth which are engaged by a pinion 25 that is mounted on a stud screw 26 that is threaded into the side of the overhead arm 40 D. This pinion 25 also meshes with the teeth of one end of a rack bar 27 that is mounted in a slideway 28 that is formed in the overhead arm D. The opposite end of this rack bar is also provided with gear teeth that mesh with a gear 29 that is mounted on the end of a short shaft 30 that is suitably journaled in a vertical bearing 31, on the overhead arm. The upper end of the shaft is also provided with a gear 32 that meshes with the teeth of one end of a rack bar 33 that is slidably mounted in a suitable bearing 34 secured upon the overhead arm. The opposite end of this rack bar is also provided with teeth that mesh 50 with a gear 35 which is preferably brazed upon the top end of a square tubular shaft 36, that surrounds loosely a solid square shaft 37. The upper end of this square solid shaft is rounded and passes loosely through the gear 35, the solid shaft having a shoulder at the junction of its round and square portions, which bears against the gear 35. This square tubular shaft extends down through the frame and passes loosely through a gear 60 38 that is rotatably mounted in a suitable

bearing on the frame in which the gear is supported against vertical movement. A rack bar 39 is reciprocally mounted in the frame and its gear teeth mesh with the gear 38. The opposite end of this rack bar is 70 pivotally connected to one end of a link 40, the opposite end of which is connected to one arm 41 of a double armed lever, which is pivotally mounted in a journal block 42, that is secured to the bed plate of the frame. 75 The upper end of the other arm 43 of this double armed lever is provided with a roller which engages a groove in one side of a cam 44 that is mounted on a cross shaft 45. This cross shaft has secured upon it a bevel gear 80 46, which meshes with and is driven by a bevel gear 47, that is mounted on the end of a main driving shaft 48. The lower end of the solid shaft 37 passes loosely through a gear 49 which is mounted in a bearing 50 85 secured to the adjacent side of the frame. The gear 49 is in mesh with a rack bar 51, the opposite end of which is connected to a link 52, the other end of which connects with one end of a lever 53, which is loosely 90 mounted on a stationary shaft 54. The intermediate portion of this lever carries a roller, which enters a groove in the opposite side of the cam 44.

The upper end of the solid square shaft 95 37 carries a gear wheel 55, the function of which will be hereinafter set forth. A somewhat similar cam 44^a of the cam 44 is secured upon the opposite end of the shaft 45, which operates a duplicate arrangement of 100 the levers and rack bars just described, which rack bars operate a duplicate arrangement 38^a and 49^a of the gears 38 and 49 and also a duplicate arrangement 36^a and 37^a of the shafts 36 and 37. The upper ends of the 105 hollow shaft 36^a carry a gear wheel 56, and the upper end of the solid shaft 37^a carries a gear wheel 57, the function of which will be hereinafter described.

Each head block is provided on its right 110 hand side with a worm pinion 58 which is rotatably mounted in bearings formed on the side of each block. Each worm pinion of each head block meshes with a toothed segment 59 that is secured on one end of a 115 pin 60, which is pivotally secured in the head block. A depending lever 61 is rigidly secured upon the pin, the lower end of which is arranged to engage a pin 62, which extends loosely through a long slot 63 formed 120 in each block, and also through a slot 64 that is formed through a plate 65 that is reciprocally mounted in a slideway 66 that is formed in the outside edge of the head block, said pin being threaded into a finger 125 blade or bar 67 which is seated in a slot formed in the outside surface of the plate 65. This finger blade is pivotally secured at its upper end by a pin 68 to the plate 65. The pin 62 is provided with a screw driver 130

head to permit it to be adjusted to receive the stroke of the lever 61 due to the reverse rotary movement of the worm by its toothed segment, as will be hereinafter explained.

5 The worms are each provided with a square axial aperture in which a square shaft 69 fits loosely, and the head blocks and their worms are arranged in alinement on the overhead arm and the square shaft 69 extends across and through and beyond both worms. Consequently the worms of both head blocks are rotated in unison, and the levers 61 engage both pins 62 at the same time and swing the lower ends of the finger blades out from the plates at the same time. The finger blades are returned into their slots on the backward stroke of the levers 61 by an expansive spring 70 which is mounted on a pin 71 that extends loosely through an aperture formed through the finger blade and is threaded into the plate 65.

10 The shaft 69 and the worms are rotated by a train of gearing in the following manner:

15 25 The pinion 55 on the upper end of the solid shaft 37 meshes with one end of a rack bar 72, the opposite end of which meshes with a pinion 73 that is secured on the end of a shaft 74, the opposite end of which is provided with a bevel gear 75 that meshes with a bevel gear 76 on the end of the shaft 69. Thus the cam through the lever arms 41 and 43 and left hand rack bar 51 imparts movement to the left hand solid shaft 37 through its pinion 49, and the gear on the upper end of this shaft operates the rack bar 72 which operates the gear 73, the lower end of whose shaft carries the gear 75, which operates the bevel gear 76 on the shaft 69, whereby the worms 58 are turned in unison, and the arms 61 thereby moved against the pins 62 to swing the plates 67 outward.

20 25 The plate 65 of each head block has a vertical reciprocal movement imparted to it of about a half inch stroke, which movement is effected in the following manner: A link 77 is pivotally secured at one end to each plate 65 by a pin 78 that extends loosely through an aperture in the finger blade and is threaded into the plate, and the opposite end of this link is pivotally connected at one end to a lever 79, the opposite end of which fits loosely on a square shaft 80 that is mounted in sleeve bearings rotatably journaled in bearings 81 that are formed on the head block (see Fig. 4). The square shaft is rounded at its rear end and extends through a bearing on the transverse portion of the overhead arm D, and a bevel gear 82 is secured to this end and the shaft is partially rotated or oscillated by a train of gearing in the following manner: The pinion 57 on the upper end of the right hand solid shaft 37^A meshes with one end of a rack bar 83,

the opposite end of which meshes with a pinion 84 that is secured on the end of a shaft 85, the opposite end of which is provided with a bevel gear 86 that meshes with the bevel gear 82 on the adjacent end of the shaft 80. Thus the movement of the right hand cam 44^A is imparted to the shaft 37^A in the same manner described in connection with the left hand cam 44, and the shaft 87, the mechanisms operating these two shafts being duplicates of each other, and located on opposite sides of the machine.

20 25 After the head blocks B and C have dropped down at a short distance behind the box, the head block B is moved forward by the pinion 25 and rack bar 27 and as its push block 1 advances to the box, the upwardly beveled bottom surface of a finger block 87 carried by the plate 67 engages the up-standing edge of the blank and bends it inwardly over the top edge of the box to the same angle as the bottom of the finger. Then the box is engaged by the push block 1 and is moved forward against the abutment block 2 of the head block C and as the box moves toward that abutment block the rear end of the box and the up-standing edge of the blank are pushed against the beveled bottom surface of the finger block 88 of the head block C, and as the rear end of the box advances under this finger the up-standing edge of the blank is bent into the box down to the edge of the box, which is engaged by the base edges of both finger blocks when the box is finally gripped between the push and abutting blocks of both heads. The finger blocks are then both raised upward vertically about a half of an inch by the movement of their links 77 and lever 79 and the square rod 80 and by the same means are then moved straight down until the heels of these finger blocks rest directly on top of the end edges of the box, when pressure enough is supplied to them through the links to firmly seat the box against the top of the table, and both finger blocks are then raised and remain up while the side turn-in mechanisms advance and turn over and in and against the inside surfaces of the box the upwardly projecting side edges of the blank. We do not, however, illustrate these side turn-in mechanisms as they do not form a part of our present invention.

25 30 Instantly after the side turn-in blades have moved against the side edges of the box on its interior, and while they are in this position, the end turn-in blocks again move down in the ends of the box; as they move down they engage the ends of the blanks at the corners, and the latter are folded over into the interior of the box and are tightly wrapped against the inside edges of the interior of the box, preparatory to the final treatment.

Our invention provides a rapid, reliable and artistic open box end wrapping mechanism.

Our present invention relates solely to the mechanical elements and combinations of the end turn-in mechanism in blank wiper mechanism only, and while we have illustrated and described the preferred construction and arrangement of it, we do not wish 10 to be limited to it, as there are many changes that might be made without departing from the spirit of our invention.

Having described our invention, what we claim as new and desire to secure by Letters 15 Patent, is:

1. An end turn-in open edge box wrapping mechanism comprising a supporting table, the end turn-in wiper heads consisting of means including the upwardly inclined 20 finger blades arranged to move down and engage the edges of the opposite ends of the box and seat said box against said table, and means for operatively actuating said heads to position, seat and wrap the open ends of 25 the box.

2. An end turn-in wiper mechanism, comprising a supporting table, the opposing end turn-in wiper heads consisting of means including the upwardly inclined finger blades, 30 the box and blank positioned in operative relation to said finger blades, said finger blades being arranged to engage said blanks and box with their inclined surfaces first by a horizontal sliding movement against the 35 opposite ends of the box toward and over the ends of said box, in combination with the adjustable overhead arm and its actuating mechanism arranged to position, seat and wrap the opposite ends of the partially wrapped boxes.

3. An end turn-in wiper mechanism for partially wrapped paste-board boxes and their gummed blanks, comprising the table provided with opposing and jointly and 45 simultaneously inwardly and outwardly moving turn-in wiper heads, said heads consisting of the finger blades arranged and adapted to wrap the blanks to the inside surface of the opposite ends of said box simultaneously, with the adjustable overhead 50 arm and its actuating mechanism arranged to position, seat and wrap the opposite ends of the partially wrapped boxes, and means including a cam controlled lever operated 55 rock bar mechanism for intermittently reciprocating said arm.

4. An end turn-in open edge box wrapping mechanism comprising the table, and means including the horizontally and vertically and outwardly tilting upwardly beveled finger blades and their supporting turn-in wiper heads, and means for operatively actuating said heads to position, seat and wrap the open ends of the box, an arm for

supporting said heads, and means including a cam actuated power driven shaft for operating said heads.

5. In a box end turn-in wiper mechanism, the combination of the table frame, the adjustable vertically reciprocating overhead arm and its operating mechanism, with the box and turn-in heads depending from said arm, the plate reciprocally mounted in each head, and the blades pivotally connected to the top of said plates to swing outwardly at their bottom ends.

6. In a box end turn-in wiper mechanism, the combination of the table frame, the adjustable vertically reciprocating overhead arm and its operating mechanism, with the box and turn-in heads depending from said arm, the plate reciprocally mounted in each head, and the blades pivotally connected to the top of said plates to swing outwardly at their bottom ends, a pin adjustably threaded to each of said heads, slots in each plate and blade through which said pin extends loosely, a head on each pin and an expansive spring on each pin arranged to bear expansively between said head and said blade whereby said blade is held under resilient tension against said plate.

7. In a box end edge wiper mechanism, the combination with a table frame, of an overhead arm supported in said frame, a power shaft in said frame, and means operated thereby and connected with the arm for imparting a reciprocating movement to the same, wiper mechanism supported on said arm, means for operating said mechanism, and mechanism operated by the power shaft for actuating said wiper mechanism operating means.

8. In a box end edge wiper mechanism, the combination with the table frame, of the wiper heads, the reciprocating and adjustable overhead arm and its supporting tubular standards and operative mechanism, a square tubular shaft concentrically and rotatably journaled in and extending through each of said standards and overhead arm, a spur gear mounted on the upper end of each tubular shaft, each of said gears meshing with one of the ends of two rack arms, the opposite ends of said rack bars meshing with pinions arranged with vertical shafts depending from them, and the horizontal square shafts and the bevel gears connecting with and driven by said vertical shafts.

9. In a box end edge wiper mechanism, the combination of the wiper heads, the overhead arm, of a square tubular shaft concentrically and rotatably journaled in and extending through each of said standards and overhead arm, a spur gear secured to the upper end of each of said square tubular shafts, each of said gears being arranged to mesh with one of the ends of two rack arms, the

- opposite ends of said rack bars being arranged to mesh with pinions provided with vertically depending shafts, the horizontal square shafts journaled in the opposite sides 5 of said overhead arm, the bevel gears connecting with and driven by said vertical shafts, said turn-in heads being adjustably mounted on said overhead arm, the worm pinions rotatably journaled in said heads 10 and mounted on one of said square shafts in sliding alinement with each other, the plate reciprocally mounted in each turn in head, the links operatively connected on the other square shaft, and means for operating said 15 square tubular shaft and said gearing connections to rotate said worm pinion and said links and their operating shafts.
10. In a box and edge wrapping mechanism, the combination with the table frame, 20 the power driven longitudinal shaft and cross shafts within said table frame, the cam on said longitudinal shaft and the fork connected to said cam, and the cross head intermittently and reciprocally moved by 25 said cam and fork, the vertical tubular standards connected at their lower ends to said cross head, the overhead arm mounted on said standards, means including a cam mounted on said cross shaft and gearing operatively connected to said cam for reciprocating said standards and overhead arm, the oppositely arranged box edge wiper heads on said overhead arm, and the opposite box edge 30 engaging wiper mechanism of each head, comprising the plates and the blades and their operating mechanism arranged and adapted to engage the opposite blank and box ends and operatively wrap said blank ends over the edges of and into the interior 35 of and against the inside surfaces of the opposite ends of said box simultaneously.
11. In a box and edge wrapping mechanism, the combination with the table frame, the power driven longitudinal shaft and 40 cross shafts within said table frame, the cam on said longitudinal shaft and the fork connected to said cam, and the cross head intermittently and reciprocally moved by said cam and fork, the vertical tubular standards connected at their lower ends to 45 said cross head, the overhead arm mounted on said standards, means including a cam mounted on said cross shaft and gearing operatively connected to said cam for reciprocating said standards and overhead arm, 50 a vertically arranged threaded rod secured at its upper end to said cross head, a cam fork provided with a roller secured to the lower end of said threaded rod, and a cam on said shaft in engagement with the roller 55 of said cam fork, whereby said overhead arm is vertically reciprocated.
